UNITED STATES PATENT OFFICE.

G. D. SPOONER AND J. F. F. HALE, OF RUTLAND, VERMONT.

IMPROVED CAR-COUPING.

Specification forming part of Letters Patent No. 57,208, dated August 14, 1866.

To all whom it may concern:

Be it known that we, G. D. SPOONER and J. F. F. HALE, of Rutland, Rutland county, and State of Vermont, have invented a new and Improved Car-Coupling; and we do hereby declare that the following is a full, clear, and exact description thereof, which will enable others skilled in the art to make and use the same, reference being had to the accompanying drawings, forming part of this specification, in which—

Figure 1 represents a longitudinal vertical section of this invention. Fig. 2 is a horizontal section of one of the draw-heads. Fig. 3 is a front view of the same.

Similar letters of reference indicate like parts.

This invention consists in the arrangement of a central horizontal partition in the draw-heads of a car-coupling in such a manner that the link or shackle bar can be readily adjusted for cars of different height, and a universal self-locking car-coupling is obtained.

It consists, further, in the arrangement of a double stop, in combination with the central partition in the draw-heads, and with the coupling-pin, in such a manner that the coupling-pin in one draw-head can be readily adjusted in the proper position to correspond to the position of the shackle-bar in the other draw-head, or to correspond to the difference in the height of the cars.

It consists, finally, in providing the shackle-bar with a hole just large enough to admit the coupling-pin, in addition to the slot generally used in shackle-bars, in such a manner that by the action of the shackle-bar the stop which sustains the coupling-pin is released under all circumstances, and the operation of the coupling is rendered sure and safe.

'A A' represent the draw-heads, which are supposed to be secured to adjoining cars.

These draw-heads are provided each with a central partition, *a*, so that the shackle-bar *B* can be adjusted higher or lower, according to the relative height of the cars. If the cars are of uniform height, the shackle-bar may be left in the upper compartment of one draw-head and made to lock into the corresponding compartment of the other draw-head; but if the cars are of different height the shackle-bar may be secured in the upper compartment of its draw-head and made to lock in the lower compartment of the other draw-head, or vice versa.

Each draw-head is provided with a coupling-pin, *b*, and with a double stop, *c*. This stop is provided with two steps, so that the coupling-pin can be sustained on the upper or on the lower stop, as circumstances or the difference in the height of the cars may require.

The shackle-bar is provided with a hole, *d*, in addition to the ordinary slot *e*. By the hole said shackle-bar is prevented from sliding back in its draw-head, and it is sure to strike and release the stop in the opposite draw-head.

By these means a car-coupling is obtained which is absolutely sure in its operation, and which is self-locking, so that the danger of being caught between the draw-heads is avoided.

What we claim as new, and desire to secure by Letters Patent, is—

The double stop *c*, in combination with the horizontal partition *a* and coupling-pin *b* of a car-coupling, constructed and operating substantially as and for the purpose set forth.

G. D. SPOONER.
